CLAIM

The ornamental design for a combined firearm suppressor core, mount body, tube, and spring, as shown and described.

DESCRIPTION

FIG. 1 is a top, front, right perspective view of a combined firearm suppressor core, mount body, tube, and spring in accordance with our new design;

FIG. 2 is a top, rear, left perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is a bottom, rear, right perspective view thereof;

FIG. 10 is another bottom, rear, right perspective view thereof;

FIG. 11 is a vertical section of FIG. 8, along line 11-11; and,

FIG. 12 is a vertical section of FIG. 8, along line 12-12. The broken lines in the drawings disclose unclaimed portions of the combined firearm suppressor core, mount body, tube, and spring only and form no part of the claimed design.
